UNITED STATES PATENT OFFICE.

CHARLES T. WAGNER, OF COLLEGE POINT, NEW YORK.

DESIGN FOR QUILTING.

SPECIFICATION forming part of Design No. 18,402, dated June 19, 1888.

Application filed January 28, 1888. Serial No. 262,301. Term of patent 7 years.

To all whom it may concern:

Be it known that I, CHARLES T. WAGNER, of College Point, Queens county, State of New York, have originated and produced a new 5 Design for Quilting, of which the following is a specification.

My design relates to quiltings which are manufactured for linings for skirts, for garments, and for bed-coverings.

10 The design consists of a combination of rows of circles so arranged that the circles of alternate rows will be opposite the spaces between the circles of intermediate rows and figures rearranged between said circles and severally consisting, essentially, of two oppositely extending figures and semicircles connecting the ends thereof.

15 The accompanying drawing represents a piece of quilting ornamented with my design. 20 a' a^2 are rows of circles. The circles of the

rows a^2 are opposite the spaces between the circles of the rows a' . Between the circles of each row are figures b' b^2 , shown as severally consisting of two opposed bracket-shaped figures 1 2 and connecting semicircles 3. These 25 figures are staggered to correspond to the staggering of the circles. Each of such figures therefore appears to be within a group of four circles.

What I claim as new, and desire to secure 30 by Letters Patent, is—

The design for quilting, consisting of staggered rows of circles and staggered rows of opposed figures composed of bracket-shaped lines and connecting semicircles, substantially 35 as shown and described.

CHAS. T. WAGNER.
